UNITED STATES PATENT OFFICE

147,785

DESIGN FOR A FRONT FOR RADIO CABINET OR SIMILAR ARTICLE

Walter Fanelli, South Euclid, Ohio, and Carl A. Laystrom, Chicago, Ill., assignors to Faries Manufacturing Company, Decatur, Ill., a corporation of Illinois

Application January 19, 1946, Serial No. 125,737

Term of patent 14 years

(Cl. D33—19)

To all whom it may concern:

Be it known that we, Walter Fanelli and Carl A. Laystrom, both citizens of the United States, and residents of the village of South Euclid, in the county of Cuyahoga and State of Ohio, and of the city of Chicago, in the county of Cook and States of Illinois, respectively, have jointly invented a new, original, and ornamental Design for a Front for Radio Cabinet or Similar Article, of which the following is a specification, reference being had to the accompanying drawing, forming a part thereof.

On the drawing:

Figure 1 is a front elevational view of the front for radio cabinet or similar article, showing our new design.

Figure 2 is a top plan view, and

Figure 3 is a side elevational view thereof.

We claim:

The ornamental design for a front for radio cabinet or similar article, as shown.

WALTER FANELLI.
CARL A. LAYSTROM.
